UNITED STATES PATENT OFFICE.

MILTON D. THOMPSON, OF FAIRHAVEN, MASSACHUSETTS.

PROPELLER OR THE LIKE.

Application filed November 9, 1927. Serial No. 232,155.

My invention relates to propeller wheels and more especially to that type of wheel in which the blades, when not revolving with the shaft, may feather or turn on their axes 5 a certain amount.

This type of wheel is quite largely used on sail craft equipped with auxiliary motor driven propulsion and is extremely valuable in case the sails are used as the propelling 10 agent.

In feathering the blades, their sharp entering edges cut the water in a plane coincident with that of the direction of travel of the boat or ship and therefore do not offer a large 15 amount of resistance to the movement of the latter when under sail power.

In some types of feathering propeller wheels a tube or sleeve is employed to actuate the blades in bringing them into feathering 20 position. This sleeve encases the shaft, extends from the propeller inboard and is operated by a lever or screw arrangement.

This style of construction necessitates a certain amount of complication in the mechanism and its operation is often attended with 25 more or less difficulties, requires constant attention and frequent repairs, which, on account of the inaccessibility of the parts, are quite apt to be expensive.

30 One of the principal objects of my invention is to provide a feathering blade which is automatic in its action, requiring no outside mechanical devices to bring it into the feathering position, depending wholly on the force 35 of the water against the rearward portion of the blade to produce the result.

Another object is to eliminate many of the parts required in the sleeve or positively operated types. In doing this I am enabled to 40 make a much stronger propeller, insuring longer life and fewer replacements. It will also relieve the engineer of the craft of all care or thought relative to the feathering of the blades, as immediately upon stopping his 45 motor the blades automatically adjust themselves to the fore and aft, or feathering position.

Other objects of my invention will be apparent from a consideration of the detailed 50 description hereinafter found in my specification when taken in connection with the accompanying drawing wherein a preferable em-

bodiment of my invention is shown and in which like characters of reference refer to similar parts in all of the several views. 55

The invention here disclosed is an improvement on the propeller described in United States Patent 1,626,056 granted to me and to which reference may be had.

In the drawings:—

Figure 1 is a view, in perspective, of my three-blade feathering propeller wheel.

Figure 2 is a longitudinal sectional elevation taken through the casing showing some parts in full. 65

Figure 3 is a view, in perspective, of my improved hub member.

Figures 4 and 5 are perspective views of the forward and rearward parts of the casing.

Figure 6 is a view, in perspective, of one of 70 the propeller blades.

Referring to the drawing, 1 is the propeller shaft, 2 is the blade, 3 is the hub of the blade and 4 is a channel in the hub. Pintles 5 and 6 are positioned on the under surface 75 of the blade hub in the manner shown in the drawing. Both pintles should be on the same side of a line passing through the center, or, in other words, the arcuate distance between them should preferably be less than one 80 hundred and eighty (180) degrees.

Secured to shaft 1 is the hub 7 which is provided with a flange 8 at one end thereof and having the tracks or stop bars 9 spaced along the periphery, the tracks being just 85 below the periphery of the flange 8 and extending from the flange to the other end of the hub. The stop bars 9 are turned at their outer ends to form the slopes 10 and 11. These slopes fulfill a function which will be 90 set forth hereinafter. Disposed about midway between each pair of stop bars is a trip bar 12 which extends one half the length of the stop bars and tapers to a point. The areas between the stop bars and trip bars provide 95 pin ways for the pintles.

The casing 12' consists of the hub-inclosing portions 13 and 14 and the conical cap 15. The hub inclosing portions are provided with complementary recesses 16, 17. The thickness of the shell at these openings being such as to fill the channel 4 in hub 3 of the blade and allows the latter to oscillate therein at certain times, but prevents its withdrawal 100

from the casing. Straps 18 are provided on the forward half of the casing, having threaded openings 19 therein by means of which a screw may be passed through the rearward half 14 into the said threaded openings and thereby secure the two halves together.

The outer end of the aft portion of the casing is provided with a threaded opening for the reception of the thrust bushing 20.

- 10 The thrust bushing has a flange portion 21 which abuts the hub 7. A washer 22 is provided and this is secured in place by the nut 23 on the shaft. The thrust bushing is of sufficient length to project beyond the rearward half of the casing and the conical end 15 is provided with a threaded interior whereby it may be screwed upon said thrust bushing into contact with the rearward half of the casing. A notch 24 may be provided in the 20 apex of the conical end to assist in its application or removal.

The hub is reduced at its outer end as shown at 21 and this reduced portion, in conjunction with the washer 22, forms a channel for the flange on the thrust bushing and prevents the thrust bushing from leaving the hub. It will be seen that by turning the thrust bushing, the casing 12 turns about the hub carrying the propeller blades therewith. As the 30 propeller blades advance along the stop bars, the outermost pintle engages the slope or bevel 10 and changes the pitch of the propeller blades. It is the function of the slope or bevel to change the pitch. By rotating the 35 thrust bushing to the right, the casing and propeller blades move backwardly and the pitch is correspondingly flattened. By rotating the thrust bushing to the left, the pitch is increased.

- 40 The mode of operation is as follows: When the propeller is going forward or aft the pintles on the propeller blades both contact either one of the opposing faces of the complementary stop bars depending upon the direction of travel. When the motive power stops, the shaft remains stationary and the resistance of the water against the back side of the blades will cause them to oscillate and cause the pintles to straddle the trip bars. 45 50 The pintles on the blade hub straddle the trip bars when the blades are in the feathering position. The trip bars assist in changing the propeller blades from ahead to reverse propulsion by acting as a bumper or trip for the rear pintle.

All that has been said above in the description of my preferred embodiment is offered by way of illustration and not limitation. I do not wish to be limited to the exact structure of the preferred embodiment shown and described, or to any particular material used in the construction of parts, or the design of parts, but desire protection as against any variations in structure which utilize the principle of my invention and fall within the pur-

view of my invention and are within the spirit and scope of the following claims:

The invention having been set forth, what is claimed as new and useful is:

1. A feathering and reversing propeller, comprising in combination a shaft, a hub fixed on said shaft, a casing surrounding said hub, propeller blades, said propeller blades being mounted in the periphery of said casing, each of said propeller blades having 70 pintle means on its base extending to said hub, said hub having alternately disposed stopping means and tripping means which provide pin-ways for said pintle means.

2. A feathering and reversing propeller, comprising in combination a shaft, a hub fixed on said shaft, propeller blades contacting said hub, pintle means on said propeller blades, stop-bars on said hub, trip bars disposed between said stop bars, said pintle 80 means being adapted to slide along said stop bars and contacting one of said trip bars to swing to the opposite stop bar whereby the propeller reverses its position.

3. A feathering and reversing propeller, comprising in combination a shaft, a hub fixed on said shaft, a casing surrounding said hub, propeller blades, said propeller blades being mounted in the periphery of said casing, each of said propeller blades having 90 pintle means on its base extending to said hub, said hub having alternately disposed stopping means and tripping means which provide pin-ways for said pintle means, and means on said casing coacting with said hub 95 whereby the pitch of said propeller blades may be regulated.

4. A propeller comprising in combination a shaft, a hub on said shaft, a casing surrounding said hub, propeller blades movably mounted on said casing, spaced anchoring means on said hub for holding said propeller blades in a propelling condition during the rotation of said shaft, means intermediate of said spaced anchoring means for actuating said propeller blades from the ahead to the reverse position, said anchoring means having a bevel thereon, a thrust member on said casing coacting with said bevel whereby the pitch of the propeller blades may be regulated.

5. A feathering and reversing propeller, comprising in combination a shaft, a hub fixed on said shaft, propeller blades contacting said hub, pintle means on said propeller blades, stop-bars on said hub, trip-bars intermediate said stop-bars extending substantially one half the distance and tapering to a point, said pintle means being adapted to slide along said stop bars and contacting one 120 of said trip bars to swing to the opposite stop bar whereby the propeller reverses its position, said base having a reduced portion, a washer of larger diameter than the hub being secured to said hub by a nut whereby a 130

channel is formed, a thrust bushing threaded into one end of said casing having a flange which is received in said channel, said stop bars having a bevel at the end adjacent said channel, said thrust bushing being adapted to be rotated and cause movement of the propeller blades along the stop bars whereby

the said pintle means are acted upon by said bevel to regulate the pitch of said propeller blades.

Signed at Fall River in the county of Bristol, State of Massachusetts, this twenty-eight day of October, 1927.

MILTON D. THOMPSON.
